ART OF COOKING HEAVY OILS

Filed March 7, 1929

UNITED STATES PATENT OFFICE

WILLIS S. GULLETTE, OF HIGHLAND, INDIANA, ASSIGNOR TO SINCLAIR REFINING COMPANY, OF NEW YORK, N. Y., A CORPORATION OF MAINE

ART OF COKING HEAVY OILS

Application filed March 7, 1929. Serial No. 345,016.

This invention relates to improvements in the coking of heavy oils, such as crudes, topped crudes, flux oils, other residual oils and the like. More particularly, this invention relates to improvements in such coking operations in which a charge of coke is formed and deposited within a coking receptacle from which this coke product must be discharged. Commercially, lump coke is more valuable than coke fines. The improvements of this invention assist particularly in increasing the production of lump coke and in decreasing the production of coke fines in such coking operations. Other advantages of the invention will be apparent as the description proceeds.

The invention is particularly useful in connection with the operations described in applications Serial No. 340,996 filed February 20, 1929, Patent No. 1,831,719, dated November 10, 1931, and Serial No. 341,214 filed February 19, 1929 by Harry L. Pelzer and Serial No. 347,533 filed March 16, 1929 by Edward W. Isom and George H. Taber, Jr., but, as will be apparent, it is of more general application.

Most of the fines produced in such coking operations are produced, not during the coking operation proper, but during the discharge of the coke product from the coking receptacle, and such fines are produced by the disintegration of what otherwise would be lump coke. This discharge of the coke product has been effected, heretofore, in a number of ways ranging from the crude digging out of the coke product to more refined methods involving the rearrangement of chains or cables within the coking receptacle so that, at the termination of the coking operation proper, the chains or cables extend through the body of the coke charge so that the coke product can be broken up within the receptacle and discharged by pulling out the chains or cables.

This invention provides for the removal of

the bulk of the coke product from the coking receptacle as large coherent blocks which can be broken up for sizing as desired with a minimum production of coke fines and a maximum production of lump coke. The discharge of the coke product from the coking receptacle is, moreover, through this invention, much simplified and much expedited, making it possible to keep the coking receptacle in use for carrying out the coking operation proper a greater proportion of the time.

According to this invention, a radially thin annulus of the charge of coke in the coking receptacle, a cylindrical coking receptacle being used, is removed immediately adjacent the wall of the coking receptacle at the termination of the coking operation proper and the remaining bulk of the coke charge is then removed as a single block or as a relatively small number of large blocks.

In carrying out this invention, a radially thin annulus of the charge of coke in the coking receptacle is removed immediately adjacent the wall of the coking receptacle by forcing an annular drill of diameter slightly less than the inside diameter of the coking receptacle through the coking receptacle at the termination of the coking operation proper leaving the bulk of the coke as a free block or blocks within the coking receptacle, and this block coke is then discharged en bloc through one or the other of the heads of the coking receptacle.

The invention will be further described in connection with the accompanying drawing which illustrates, diagrammatically and conventionally, one form of apparatus adapted for the practice of the invention, but it is intended and will be understood that this more detailed description and illustration are simply by way of exemplification.

Referring to the drawing, the coking operation proper is carried out in the coking receptacle 1, the heavy oil stock to be reduced

to coke being sprayed into the upper end through connection 2, the hot vapors from a vapor phase cracking operation, for example, being released within the lower end 6 through connection 3, and the vapor mixture resulting from the coking operation being discharged through connection 4. The coking operation proper may be carried out, for example, as described in any of the applications Serial Nos. 340,996, 341,214, or 347,533 mentioned above. The coking receptacle 1 may, for example, be a drum 9' in diameter and 30' high. The coking receptacle 1 is provided with an upper head 5 and a lower head 6. The lower head 6 is of the full diameter of the coking receptacle. This large diameter head may be sealed, for example, as described in application Serial No. 344,940 filed March 7, 1929, Patent No. 1,819,095 dated August 18, 1931, by Eugene C. Herthel. During operation, the plate 7, somewhat smaller in diameter than the receptacle 1, is supported just above the lower head 6 by means of a cable 8 extending through a gland 9 in the upper head 5.

In carrying out the invention with the apparatus illustrated, at the termination of the coking operation proper, the lower head 6 is removed from the coking receptacle 1 and an annular drill 10 of diameter slightly less than the inside diameter of the coking receptacle 1 and slightly more than the outside diameter of the supporting plate 7 is forced upwardly through the accumulated charge of coke leaving the bulk of the coke as a free block or blocks supported by the cable 8 and the plate 7. The drill 10 is then withdrawn from the coking receptacle and the remaining coke charge is then lowered out of the coking receptacle by means of the supporting cable 8. The coking receptacle is then closed, with the supporting plate 7 in place therein, and the operation resumed, as described. No further cleaning of the coking receptacle is usually necessary.

The mechanism illustrated for driving the annular drill 10, comprises a shaft 11 carried by a hydraulic jack 12 and slidably keyed to a gear 13. The gear 13 is mounted on a carriage on which is also mounted a rotary steam engine 14 for driving the gear 13 through pinion 15. A jack 12 and shaft 11 are usually provided for each coking receptacle in a battery of coking receptacles. The driving mechanism is mounted on a carriage to permit the use of a single driving mechanism in connection with any of a number of coking receptacles. When in use in connection with any one coking receptacle, the carriage carrying the driving mechanism is supported by means of jack screws 16.

I claim:

In the coking of heavy oils with the formation of a charge of coke in a cylindrical coking receptacle and the removing of the

coke charge from said receptacle with an annular drill, the improvement which comprises reducing a charge of heavy oil to coke in said receptacle and, at the termination of the coking operation proper, removing a radially thin annulus of the charge of coke immediately adjacent the wall of the coking receptacle by forcing the said annular drill through the receptacle, and then removing the remaining bulk of the coke body en bloc. 70 75

In testimony whereof I affix my signature.

WILLIS S. GULLETTE.
